UNITED STATES PATENT OFFICE

JACOB H. LE MONTREE, OF CINCINNATI, OHIO, ASSIGNOR TO THE LE MONTREE MANUFACTURING COMPANY, OF CINCINNATI, OHIO, A CORPORATION OF OHIO.

GARMENT BAG

Application filed September 11, 1926. Serial No. 134,889.

My invention relates to bags for use in the storage of wearing apparel and other garments.

It is the object of my invention to provide a side opening bag, having a closure which will secure garments held within it from moths, dirt, dust or moisture, and includes means for supporting garment hangers in its upper portions, said upper portion being so built as to be simple to make, and stout and strong, relieving the bag from strain of the garments, and reinforcing the upper edge of the bag as well.

I accomplish my objects by that certain construction and arrangement of parts to be hereinafter more specifically pointed out and claimed.

In the drawings:—

Figure 1 is a perspective view of the bag with the sealing flap open.

Figure 2 is an elevation of the bag, showing in dotted lines the contents thereof.

Figure 3 is a detail of the top bar and hook structure of the bag.

Figure 4 is a section on the line 4—4 of Figure 1.

The bag may be conveniently formed of a piece of paper 1 as long as the bag and of double width, which is folded along the middle as at 2, and lapped at the bottom and pasted as at 3, forming a preliminary structure which is open along one side and along the top.

The side flap is preferably formed, although not necessarily, of a piece of gummed tape 4, which is secured to one edge of the bag so as to leave plenty of surface to be later bent over the other edge of the bag and sealed down, thus closing the bag along the side and about whatever contents may have been placed therein.

The top of the bag is formed preferably as follows: A piece of gummed tape 5 is secured with its edge adhesively engaging the top edges of the main bag body, leaving sufficient upward extension to form a loop closing the top of the bag. A strip of wood 6, having a supporting hook and a garment hook as will be described, is set into and adhesively secured to the upward extension, formed

as a loop with its supporting hook protruding through a punctured hole in the loop of the tape. If desired, an additional piece of gummed tape 7 may be extended across the strip 6 and around the sides of the piece of wood with its gummed side outermost. In this modification the strip is held in position by means of the hook extending through the punctured hole.

These particular details of structure while making for economy, are not essential to the function developed by the bag.

As a preferred structure of the hook elements, a piece of wire is bent to form the upper supporting hook 8, and passed through the wooden strip, bent out and formed into a loop serving as a hook as at 9, and then thrust back into the wooden strip again, to anchor it, as at 10. The one piece of wire serves all purposes and the use of the hook 9 to support a garment hanger within the bag, will not place any substantial strain on the piece of wood.

In use, the garment hanger indicated at 11 will be used to suspend a garment such as the coat 12. The hanger with its garment thereon is thrust into the bag through the open side, and set over the hook 9. The sealing flap along the side is then moistened and closed, resulting in completely enclosing the structure.

There is no loose hook passing through the top of the bag with a hanger on its under end, and the top of the bag stays without sagging, due to the insertion of the piece of wood through which the hook structure is arranged. The whole device may be compactly condensed for shipment and storage, and will be suitable for hanging in a closet or elsewhere without danger of being torn due to carelessness by the users of the place of storage.

Having thus described my invention what I claim as new and desire to secure by Letters Patent is:—

1. In a garment bag, a body formed of a piece of paper folded to form side walls of a bag open at the top, bottom and along one side, extensions of the piece at the bottom and along the open side providing means for closing said side and bottom openings, a

strip of gummed tape formed as a loop providing a top closure for the bag, and a reinforcing strip having an exterior support and provided with means for supporting a garment interiorly of the bag secured in the loop of the gummed tape.

2. A garment bag having a strip of gummed tape formed as a loop providing a top closure for the bag, and a reinforcing strip having an integral wire forming an exterior support and a depending loop within the bag, said strip being secured within the loop of gummed tape.

3. A garment bag having a strip of gummed tape formed as a loop providing a top closure for the bag, and a reinforcing strip having an integral wire forming an exterior support and a depending loop within the bag, said strip being secured within the loop of gummed tape, and said depending loop having its end anchored in said strip.

JACOB H. LE MONTREE.
